UNITED STATES PATENT OFFICE.

JOHN KOPP, OF CINCINNATI, OHIO.

VIOLIN.

SPECIFICATION forming part of Letters Patent No. 243,073, dated June 21, 1881.

Application filed March 14, 1881. (No model.)

To all whom it may concern:

Be it known that I, JOHN KOPP, a resident of the city of Cincinnati, in the county of Hamilton and State of Ohio, have invented certain new and useful Improvements in Violins, of which the following is a specification.

My improvements relate to that class of string musical instruments which have a sounding-board and a back united together by an interposed rib or ribs located at or near the edges of the sounding-board and back. In these instruments the string or strings are held in position by the pin or pins in the neck and by the tail-piece at the lower end of the instrument. In the violin and other instruments of similar construction—as, for example, the viola, violoncello, violone, and bass-viol—the strings are deflected out of a straight line by what is known as the “bridge,” which latter is interposed between the strings and the sounding-board at a point near the middle of the latter. The sounding-board is secured to the ribs by glue. In violins the sounding-board is usually stiffened underneath by a longitudinal brace glued to the under side thereof, but not reaching the back, and is also braced by a post located under that portion of the board on which the bridge rests, and extends transversely across the instrument from the board to the back. The object of these braces is to brace the sounding-board, and the better enable the latter to withstand the immense pressure and strain to which it and the ribs are subjected. This pressure and strain arises from the direct tension of the string or strings. Each string of an ordinary violin will usually sustain a longitudinal strain of twenty-five pounds. Nevertheless, the strain produced by the winding up the pin in the neck is often sufficient to break the string.

It is safe to affirm that each string of a violin, while in use, is subjected to a longitudinal strain of sixteen pounds, and as there are four strings the neck, rib, and sounding-board participate in a strain of sixty-four pounds. This strain is a great impediment to the successful and perfect operation of the sounding-board, for the following, among other reasons, viz: The sounding-board being arched away from the back, the longitudinal strain to which it is subjected tends to prevent its vibration toward

the back, and the vertical pressure of the bridge upon the arch of the board tends to prevent it from vibrating away from the back. The strain upon the instrument also tends to rack it, and particularly is this the case because the sounding-board is rigidly glued to the ribs and has no opportunity to meet the strain in an elastic manner.

I have discovered, by frequent experiment, that the interposition of a thin layer of cork between the sounding-board and the ribs contributes to remedy the aforementioned defects, as well as other defects, to be hereinafter mentioned, in the construction of the instrument.

In order to make my invention more fully understood, I will now describe the same in detail.

In the accompanying drawings, Figure 1 is a view, in perspective, of all of a violin excepting the upper part of the neck and connections, the sounding-board being in part broken away to show how my improvement is applied in the construction of the instrument. Fig. 2 represents a transverse section of a part of the sounding-board, rib, and the layer of cork, and illustrating their preferred relative positions and sizes to one another; and Fig. 3 is a vertical transverse section of the body of the instrument shown in Fig. 1, taken at the dotted line *xx*, Fig. 1.

A designates the body of the instrument, B the sounding-board, C the ribs, and D the back. The tail-piece E is suitably secured, in the usual manner, to the lower end of the body A, and the strings F are strung, as usual, from this tail-piece to the pins of the neck H, the first portion of which is shown in Fig. 1 of the drawings. The strings rest upon the bridge K. A thin layer of cork, M, lies upon and is glued to the upper edge of the rib C. The latter is formed in any of the customary ways, and is here shown as consisting of the vertical piece *n* and the customary corner bracing-strips *n'*, tightly glued to the vertical pieces *n*. The layer M of cork extends over the top of the vertical piece *n*, and also, as shown, preferably extends over the top of the upper bracing-strip, *n'*, and is glued to both of the pieces *n* and *n'*. The sounding-board B rests upon the layer M of cork, and is tightly glued thereto.

In practice it is found that this layer of cork,

apparently insignificant, accomplishes great results. As it is resilient, it allows the sounding-board, under pressure, to expand or contract, and also allows the board to vibrate up 5 and down in answer to vertical pressure or the vibration of the strings, thereby allowing the sounding-board free play and enabling it to give forth a stronger and purer quality of tone.

Another advantage derived from my improvement is as follows, viz: It frequently becomes necessary in string-instruments to remove the sounding-board from the ribs. This necessity most frequently arises from the sounding-board being split or cracked or otherwise 15 damaged. As the sounding-board is the most valuable part of a good, and particularly of an old, violin, and a new sounding-board, if substituted for the old one, would, in all likelihood, be inferior to the old and well-tried 20 board, with all its imperfections, it becomes greatly desirable to save such board, and, after repairing it by strips glued upon its inner side, or in any other preferred way, to replace it again upon the body of the instrument. As 25 the sounding-board is ordinarily glued to the ribs much difficulty exists in separating it therefrom, and in so doing the wood of the sounding-board, or of the ribs, or both are frequently split or otherwise injured, thus, particularly when the sounding-board is injured, 30 injuring the instrument and its musical capacity.

My improvement, as will be perceived upon a moment's consideration, enables the sounding-board to be quickly removed from the body 35 of the instrument without injury to the ribs, or

to the sounding-board itself. This separation and removal is effected by running a knife around the instrument through the cork layer M. Usually the layer of cork is not materially 40 affected by the action of the knife. Should, however, the existing layer M of cork be badly injured by the action of the knife the remains of it can be readily scraped off from the ribs and sounding-board and a new layer 45 of cork substituted for the old one, the new layer being glued to the ribs and the sounding-board in substantially the same manner as has been mentioned of the old layer. When desired, another layer of cork may be interposed between the ribs and back and connected to same in substantially the same manner that a layer of cork is placed between the ribs and sounding-board, and connected thereto. Such a cork layer between the ribs and back will 50 enable the ribs and back to be readily and safely separated from each other. 55

What I claim as new and of my invention, and desire to secure by Letters Patent, is—

1. In a violin or similar musical instrument, 60 the combination of the sounding-board, ribs, back, and a layer or layers of cork, substantially as and for the purposes specified.
2. In a violin or similar musical instrument, 65 the combination of the sounding-board, ribs, back, and a layer of cork interposed between the sounding-board and the ribs, substantially as and for the purposes specified.

JOHN KOPP.
